UNITED STATES PATENT OFFICE.

JOHN W. COLLINS, OF WASHINGTON, DISTRICT OF COLUMBIA, ASSIGNOR OF
ONE-HALF TO JOHN FREDK. ATZEL, OF SAME PLACE.

STOPPER FOR BOTTLES.

SPECIFICATION forming part of Letters Patent No. 407,169, dated July 16, 1889.

Application filed May 13, 1889. Serial No. 310,497. (No model.)

To all whom it may concern:

Be it known that I, JOHN W. COLLINS, of the city of Washington, in the District of Columbia, have invented certain new and useful Improvements in Stoppers for Bottles; and I do hereby declare the following to be a full, clear, and exact description of the same, reference being had to the accompanying drawings, forming a part of this specification, 10 and to the figures and letters of reference marked thereon.

In the class of stoppers applied to bottles to which my improved stopper is particularly well adapted for application it is found desirable to employ a substance which will not impart a taste to the liquid coming in contact therewith or deteriorate by long contact with the liquid—such as cork—and while such substance is largely employed in lieu of rubber 15 and other substances for the sake of the quality mentioned, as well as to cheapen the cost of corking, as corks, by reason of their peculiar elasticity, may be rapidly and easily inserted in the mouths of the bottles by means 20 of compressing-machines under such pressure as to prevent all liability of the escape of even the slightest amount of the contained liquid, difficulty has been experienced in producing a stopper having the qualities mentioned 25 which can be readily withdrawn from the bottle and reinserted or reused a number of times and still form a perfect closure as well as cover the mouth of the bottle and present a finished appearance after having 30 been once removed.

Various attempts have been made to produce a stopper which shall combine the desirable qualities mentioned, but have almost universally failed of success, for the reason 35 that the stoppers could not be inserted by a machine as conveniently and securely as a plain cork. This has resulted in the adoption of the ordinary plain cork with wires or cords applied after the cork is in place to prevent 40 its accidental escape, and in some instances, when not desirable to fasten the cork in, cork-screws are inserted after the cork is in place 45 to facilitate the removal, and, in other instances, caps have been permanently fastened 50 to the cork for covering the whole mouth of

the bottle; but these latter are open to the objection above pointed out regarding the facility of application, while the former do not accomplish the desired results, as no cap is provided for the top of the bottle. 55

My invention has for its object to overcome the difficulties pointed out, to which ends it consists in a stopper having a cork for closing the mouth of the bottle, which may be inserted in any desired manner or by any of 60 the ordinary machines now in use, with a cap covering the top of the cork and extending down around the mouth of the bottle, with means for securing the stopper in place and enabling it to be easily withdrawn without 65 the employment of a corkscrew or other implement; and the invention further consists in certain novel details of construction and combinations and arrangements of parts, as will be hereinafter described, and pointed out 70 particularly in the claims at the end of this specification.

In the accompanying drawings, Figure 1 is a perspective view of a bottle and stopper constructed in accordance with my invention. 75 Fig. 2 is a similar view of a slightly-modified form of stopper. Fig. 3 is a vertical sectional view, Fig. 1. Fig. 4 is a side elevation, Fig. 2, with the locking piece or bail raised in position to draw the cork out. Fig. 5 is a sectional view of a modification.

Similar letters refer to the same parts.

The bottle A may be of any ordinary kind, with the neck or depression forming the shoulder B, to retain the fastening-wire. Within 85 the mouth of the bottle is inserted by any convenient means (a machine, or otherwise) a cork C, of the usual length for bottles containing liquid under pressure. After the cork is in place a cap D, having the depending 90 outer edge d for covering the whole top of the bottle, is applied and united to the cork by means of a central spiral or screw E, which passes down into the cork, but not way through, so as to come in contact with the 95 liquid in the bottle.

To the top of the cap is pivoted a bail, which may be in the form of a ring F, Figs. 1 and 3, or of a fastening wire or catch G, Figs. 2, 4, and 5. When arranged as shown in Figs. 1 100

and 3, the bail or ring serves as a convenient means for withdrawing the cap and its attached stopper; but when so arranged, and it is desirable to fasten the stopper in place, 50 5 cavities *f* are provided in the cap on each side of the ring, in which a wire *h* fits, the ends of the wire being held by the neck-wire in the well-known manner, or, preferably, as shown in the drawings, wherein it will be seen that 55 10 the neck-wire is twisted on one side, forming the ear *h'*, then passed around the neck of the bottle and united, one strand *h* then being passed up over the cap and given a turn or two around the ear *h'*. 60 15 With the device shown in Figs. 2, 4, and 5 the bail performs the functions of both the wire *h* and ring *F*, being for this purpose pivoted on top of the cap and provided with the side pieces having the hook-shaped catches 65 20 *g* at the ends, which pass under the ears *h'*, one being formed on each side or under the shoulder formed by the neck, in the well-understood manner. The ends of the wire forming the catch-wire are passed around to the 70 25 back of the catches and twisted together, preferably in the form of a handle *g'*, to facilitate the release of the catches and enable the catches to be released and the stopper removed by one movement, as will be readily understood. 75 30

The spiral or screw uniting the stopper and cap may be secured in the cap in any desired manner, two preferred means being shown in the drawings, one in Fig. 3, wherein it is 80 35 simply screwed in, and the other in Fig. 5, wherein it is passed through the cap, being preferably flattened for the purpose, and has the bail passed through its upper end, holding it securely in place and insuring its turning 85 40 with the bail when the cap is being applied to or removed from the cork.

The parts of the stopper constituting the present invention, it will be seen, are simple, cheap, and durable, the cap, if desired, being 90 45 cast or stamped and the bail and screw formed

of malleable iron, and, although the catches may be constructed to grasp the neck of the bottle in the well-known manner, I prefer to employ the neck-wire with suitable ears for co-operating with said catches. 95

It is also obvious that, if desired, the cap and stopper may be permanently connected to the bottle, as by a chain *w*, or other convenient device, as shown in Fig. 1. 100

Having thus described my invention, what I 105 55 claim as new, and desire to secure by Letters Patent, is—

1. In a bottle-stopper, the combination, with the cork fitting within the mouth of the bottle for closing the same, of the cap extending down around the top of the bottle, removably united to the cork by the spiral or screw, which passes only partially through the latter, whereby the cap may be applied to the cork after the same is in place, substantially as described. 110 60

2. In a bottle-stopper, the combination, with the cork fitting within the mouth of the bottle for closing the same and the cap extending down around the top of the bottle, removably secured to the cork, of the bail pivotally connected to the top of the cap and free to swing up to enable the cork to be withdrawn, substantially as described. 115 70

3. In a bottle-stopper, the combination, with the cork fitting within the mouth of the bottle for closing the same, the cap having the long depending edge entirely surrounding the top of the bottle and removably united to the cork by the screw or spiral secured to the cap and entering the cork, of the neck-wire having the ears thereon, the bail pivoted freely on the cap and having the hooked portions engaging said ears to hold the stopper in place, and the handle to facilitate the removal of the cork, substantially as described. 120 75

JOHN W. COLLINS.
